FINDING AND IDENTIFYING DEVICE

Karl Ivan Lennart Skoog, Bandhagen, Stockholm, Sweden, assignor to Telefonaktiebolaget L M Ericsson, Stockholm, Sweden, a corporation of Sweden

Application January 23, 1957, Serial No. 635,775

Claims priority, application Sweden February 4, 1956

3 Claims. (Cl. 179—18)

The present invention relates to a device for finding and identifying a marked, for example calling or idle circuit in a telephone system, wherein the marking is indicated by changing the polarity of one of a group of wires (single wire identifier). The wires are grouped to form a coordinate system. The coordinates may e.g. represent the units and tens digits, respectively, of the designations of the circuits. There are known numerous solutions of the identifying problem. The drawbacks of these solutions are that in some cases expensive equipments or complicated "and"-circuits having three conditions for operation or similar are required for selecting the desired line, and that in other cases (especially relay identifiers) a long time is required for identification.

The present invention is based upon delay lines, especially magnetostrictive delay lines and it affords a very inexpensive and reliable solution. The invention also permits the simultaneous identification of a plurality of calls. The device according to the invention can be designed for a varying number of circuits and with aid of different grouping methods. In the following embodiment of the invention showing a line identifier having 100 calling lines will be described and a suitable grouping plan has been selected, viz. a coordinate system having ten horizontal and ten vertical coordinates. The horizontal coordinates indicate the tens digit of the calling line (circuit) and calling line (circuit). At each cross point between the coordinates there is connected a so called "and"-circuit between the calling line and a reading wire, said reading wire being the horizontal coordinate and the outputs of said "and"-circuits being connected to the vertical coordinates. The condition for actuating the "and"-circuit is that the vertical coordinate receives a voltage when simultaneously a call potential appears and a voltage appears on the horizontal coordinate pertaining to the calling circuit. The identifier also includes a device for selecting one of a plurality of possible simultaneous calls.

The invention will be described more in detail in connection with the accompanying drawing in which:

Fig. 1a shows the principle of a magnetostrictive delay line according to the invention.

Figs. 1b-1d show embodiments of the "and"-circuits.

Fig. 2 shows an identifier for 100 calling circuits which is adapted for lock out.

Fig. 1a shows a nickel wire delay line N having the length 1, said said wire being provided with input coils S₁ and S₂, permanent magnets P₁-P₄, output coils M₁ and M₂ and amplifiers F₁-F₄. The permanent magnets P are used for setting up a magnetic field in the nickel wire N. If an impulse is applied at the input A the winding S₁ is actuated and thereby the magnetic field in the wire adjacent to S₁ is changed. This field change generates an acoustic wave which propagates on one hand against Q and on the other hand against R. After a time proportional to the distance between the input coil S₁ and the output coil M₁ the acoustic wave arrives at the output coil M₁ and actuates the magnetic field there. An impulse is induced in from the output coil M₁ which

impulse is amplified in the amplifier F₃. If an impulse is simultaneously applied at both S₁ and S₂, two acoustic waves are obtained which arrive at the output coil M₁ with a time difference proportional to the difference 5 between input coils S₁ and S₂. The impulses of course appear also at the output coil M₂ but at a later time which is determined by the distance between coils M₁ and M₂.

Fig. 1b shows an example of a basic "and"-circuit 10 having two relay contacts K₁ and K₂ and a known output U₁. Fig. 1c shows an electronic equivalent having rectifiers I₁, I₂, resistors R₁-R₃, inputs E, F and a known output U₂, and Fig. 1d shows an electronic equivalent comprising a resistor R₄, a condenser C₁, inputs G and H and an output U₃. If a sufficient voltage

$$V_1 + V_2 = \text{plus } (+)$$

is to be obtained at an output U₃ a voltage is required at both the inputs G and H (Fig. 1d). The time-voltage 20 diagrams above and below Fig. 1d show the voltage V₁ on the input G which is applied at the time t₀, the voltage V₂ on the input H which is applied at the time t₁ and the voltage V₁+V₂ on the output U₃ from the time t₀ to t₂.

Fig. 2 shows an identifier for a number of calling 25 circuits, comprising delay lines N₁, N₂, N₃, amplifiers F_s, F_m, F₀-F₁₉, G₀-F₁₉, bistable circuits B₀-B₁₉, "and"-circuits O₁-O₉ and O₀₀-O₉₉, input coils S₀-S₉ and T₁ and T₂, output coils M₀-M₂₀, resistors R₅-R₉ and condensers C₅-C₉ comprised in the "and"-circuits and rectifiers L₅-L₉ for preventing back current paths. The calling lines are grouped in ten vertical columns V₀-V₉ and 10 horizontal rows H₀-H₉.

Only the "and"-circuits O₉₀, O₉₁ and O₉₉ which are of the kind shown in Fig. 1d, are completely shown.

35 The delay lines N₁ and N₃ are of the recirculating kind, that is, the last receiving coils M₉ and M₁₀ respectively are connected to the input coils T₁ and T₂ respectively. The timing of the pulses is controlled by clock 40 pulses which by means of the "and"-circuits O₁ and O₂ respectively control the time position of the pulses on the delay lines N₁ and N₃. The "and"-circuits O₁ and O₂ are open only when pulses are present, both on the outputs from the coils M₉ and M₁₀ respectively and the clock pulse line. The fed back pulses are amplified by 45 amplifiers F_s and F_t respectively.

The operation of the identifier is as follows:

When an impulse is recirculating in the delay line N₁, the receiving coils M₀ to M₉ are sequentially generating output pulses as the acoustic wave is passing the coils.

50 The distance between the coils is such that the time interval between the pulses on adjacent coils is for instance 100 microseconds. When an impulse for example is emitted from the coil M₉, it is amplified by the amplifier G₉ and applied to the horizontal conductor H₉ which is 55 connected to the condenser input of all the "and"-circuits of the ninth row, that is, the "and"-circuits pertaining to the subscribers N₀ 90-99. The subscribers are each provided with a switch contact which is connected to a positive potential when the subscriber is calling, but is otherwise connected to a negative potential. In the drawing only one 60 of the subscribers, namely N₀ 99 is shown in the calling state and therefore only the output of the "and"-circuit O₉₉ will generate an impulse as the contact K₉ is the only in the ninth row which is connected to a positive potential.

65 This impulse is applied to the column conductor V₉ and via the amplifier F₉ to the input coil S₉ on the magnetostrictive delay line N₂. An acoustic wave is caused in the magnetostrictive line which propagates along the line to the coil M₂₀.

70 The time delay between consecutive input coils on the delay line N₂ is a fraction of the time delay between consecutive output coils on the delay line N₀. If, as is shown

in the drawing, the delay time between consecutive coils on the delay line N_1 is 100 microseconds, the delay time between consecutive coils on the delay line N_2 is selected to be ten microseconds for ten vertical conductors V_0 to V_9 . The distance d_4 between the last input coil S_9 and the output coil M_{20} is in the embodiment selected to be 100 microseconds. If pulses are simultaneously applied to all the vertical conductors V_0 to V_9 , they will thus be received ten microseconds separated during the time interval 100 to 190 microseconds after the pulse is applied. Thus the impulse which was applied to the horizontal conductor H_9 thousand microseconds after the same impulse was generated by the input coil T_1 will arrive at the output coil M_{20} eleven hundred microseconds after the scanning pulse was initiated by the coil T_1 . By means of the recirculating delay line N_3 a second pulse source with ten outputs is obtained where the pulses of adjacent outputs are ten microseconds time displaced. As is mentioned above, the recirculation on the delay line N_3 is controlled by the same clock pulses which control the recirculation on the line N_1 and thus each of the pulses which arrive at the output coil M_{20} will be in phase with one impulse obtained from one of the outputs of the delay line N_3 . Thus the impulse originating from the "and"-circuit "99" will be in phase with the pulse of the coil M_{10} . The latter pulse is after amplification in an amplifier F_{19} applied to one input of an "and"-circuit O_5 the other input of which is connected to the output coil M_{19} . When the impulses from M_{20} and M_{19} are coincident a trigger pulse is obtained from the output of the "and"-circuit O_5 which triggers the bistable circuit B_9 indicating the units digit "9" of the calling subscriber. When the circuit B_9 has operated an output voltage is obtained therefrom on the wires which is applied to one input of the "and"-circuits O_6 to O_9 . Said output voltage, however, does not appear until the next pulse has been emitted from the output coil M_0 and thus said pulse does not open the "and"-circuit O_8 . However, when the impulse through the delay line N_1 arrives at the output coil M_1 both the impulse of the "and"-circuit O_9 are conditioned for passing an impulse to the output. The output pulse of the "and"-circuit O_9 triggers the bistable circuit B_{19} which indicates the ten digit of the calling subscriber. Now both the digits of the calling subscriber's number are identified. In order to prevent more than one subscriber from being identified at one time and to prevent false identifications an inhibit circuit (not shown) may be arranged which prevents more than one output pulse from the output coil M_{20} from triggering more than one of the bistable circuits B_0 to B_9 at a time. In the same way precautions may be taken such that only one of the bistable circuits B_{10} to B_{19} can be operated. Thus only one of the bistable circuits B_0 to B_{19} and one of the bistable circuits B_{10} to B_{19} can be operated during one and the same identification operation until the inhibit condition is removed after a completed identification.

By means of arranging additional suitably spaced out-

put coils on the delay line N_2 further identification operations can be made simultaneously.

The invention is applicable not only to line identifiers, but it can as well be applied in other circuits for finding and identifying calling or idle circuits, particularly in electronic telephone systems.

I claim:

1. In a device for finding and identifying a marked circuit element among a plurality of similar elements, in combination, rows and columns of conductors forming a coordinate system, a coincidence circuit individual to each element and having at least two inputs and one output at each cross point between a row conductor and a column conductor, the column conductor being connected to the output and the row conductor being connected to one input, the second input of each coincidence circuit being connectable to a source of marking potential in the respective circuit element, means for sequentially applying mutually time displaced scanning pulses to said row conductors causing a pulse at the outputs of the coincidence circuits having a marking potential on the second input, a delay line having a plurality of equally spaced inputs, each connected to one of the column conductors and at least one output for separating pulses simultaneously applied to said column conductors in time, the delay time between the first and last input on said delay line being less than the interval between successive scanning pulses, and means for separating at least one of the time distributed pulses appearing on said output by means of coincidence with a selection signal having the corresponding time position.

2. A device as claimed in claim 1 wherein said means for separating at least one of the time distributed pulses appearing on the output of the delay line comprises a cyclically operating recirculating delay line having the same number of equally spaced outputs as the number of column conductors, the period of said pulse source being completed during the interval between consecutive scanning pulses, a two input coincidence circuit for each phase output having a first input connected to the delay line output and the second input connected to the pertaining phase output, and bi-stable circuit means each indicating a column containing a marked element, the output of the last mentioned coincidence circuits being each connected to a respective one of said indicating devices.

3. A device as claimed in claim 2 and comprising means for indicating coincidence between the scanning pulses and the operation of any of said bi-stable circuit means, second bi-stable circuit means each indicating a row containing a marked element, each of said means being connected to a respective one of said second bi-stable circuit means.
